Milling Machine.

Patented Mar. 30, 1830.

Charles Daniels, citizen of Middletown,
Setters Patent. (Patented, March 30, 1830.)

The Schedule referred to in this Setters Patent, is, making part of the same, containing a description in the words of the said Charles Daniels, himself, of his improvement in a Machine for cutting the scars of timblets, which invention he has assigned in due form of Law to Charles Daniels, of Saybrook, Middlesex County, Connecticut, which assignment is recorded in the Patent Office, in the Book of Transfers, Pages 254 & 255.

Be it known, that I, Charles Daniels, of the Town of Saybrook, in the County of Middlesex, in the State of Connecticut, have constructed, made, & applied to use a new & useful improvement in a Machine for cutting the scars of timblets, as invented and suggested by William W. Southworth (whose right & interest is hereinafter assigned to me); & that the following is a full & exact description of the construction & operation of the said Machine as improved by said Southworth and myself.

This Machine is generally placed upon a bed or basement of wood two feet long, eight inches wide & three inches thick. The buzz arbor is placed about two inches from the back side of left hand end of the bed, in two poppet heads, with suitable boxes to sustain it about three inches above the top of the bed. This arbor is made of cast steel, with suitable points or ends to run in the before mentioned boxes, is about eight inches long, & one half an inch in diameter, with proper shoulders or collars to receive the buzz, which is placed about two inches from the right hand end between the collars upon the arbor. This buzz, which should be made of hard cast steel, from one to three inches in diameter, & three eighths of an inch thick, with its periphery turned to form two cutting parts or edges at suitable distances from its cutting the double scar of a timblet at one & the same operation.

The timblet to be cut is placed in a vice similar to a holdmills or Hatchimakers vice, to which vice a screw is connected which plays nearly horizontally & in a direct line with the gamble thru two standards or poppet heads raised from the carriage a suitable height to receive the scar about one & a half inches above the carriage bed.

This scar must have a third depth, it passes thru the right hand standard

or propell head as coarse or equal to the double edge of the buzz or a double thread of the scow in the bimblet. Its use is to guide and propel the bimblet, or in order to move it back wards while cutting. The carriage bed is about seven inches long, five inches broad, & three fourths of an inch thick, & is made to turn upon a pivot or screw which is placed about one inch from the back side of the carriage, from the right hand end of the bed. This pivot or screw fastens the carriage to a wedge of the same length & width as the carriage bed, and about three inches thick at the right, & one and a half inch at the left end, causing an incline of the carriage to the bed, and should be placed upon the main bed at a suitable angle to bring the threads of the bimblet about square with the buzz.

This machine may be put in motion by any convenient power being applied to a band leading over a small wheel on the left hand end of the buzz arbor.

or the operator applying his right hand to a crank upon the right hand end of the pivot screw shaft, & his left hand to a handle fixed to the front corner, the left hand end of the carriage, to bring the bimblet in contact with the buzz.

What I claim as new & by virtue of said William M. Southworth's assignment to me, as my own invention or discovery in the above described machine for the use of, which I ask an exclusive privilege is the application of the double edged buzz, by which both scows of a bimblet may be cut at the same time, & by the same operation.

In testimony whereof, I have hereunto set my hand & seal this 22 day of February A. D. 1830.

Whereas I, William M. Southworth, of Saybrook, in the County of Middlesex & State of Connecticut, claim to have invented an improvement in the art of cutting the scows of bimblets by means of a double buzz, or a buzz with two edges made & applied in the manner described in the foregoing specification, and in consideration of five dollars receive all my full satisfaction of Charles Daniels of said Town of Saybrook, for myself, my heirs & legal
